UNITED STATES PATENT OFFICE.

WILLIAM W. FARNSWORTH, OF LITTLETON, COLORADO.

RENOVATOR.

1,247,654.

Specification of Letters Patent. Patented Nov. 27, 1917.

Application filed January 26, 1917. Serial No. 144,572.

To all whom it may concern:

Be it known that I, WILLIAM W. FARNSWORTH, a citizen of the United States, residing at Littleton, in the county of Arapahoe and State of Colorado, have invented certain new and useful Improvements in Renovators, of which the following is a specification.

This invention relates to improvements in renovators, and one of the objects of the same is to provide an improved apparatus of this character, whereby a blast of air, may be employed for removing and picking up dirt and foreign particles from the surface or article to be renovated.

A further object is to provide improved means whereby the dust laden air may be cleaned or purified of the dirt, and the clarified air again used as a blast against the surface to effectively and thoroughly clean and renovate the same.

A further object is to provide an improved self-contained and portable apparatus of this character, which will be simple, durable, cheap and compact in construction and easy to manipulate.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating the invention and in which:

Figure 1 is a vertical sectional view of an improved apparatus of this character, constructed in accordance with the principles of this invention.

Fig. 2 is a vertical sectional view as taken on line 2—2, Fig. 1.

Fig. 3 is a detail view of one of the filter wings.

Fig. 4 is a detail sectional view as taken on line 4—4, Fig. 1.

Fig. 5 is a view partly in side elevation and partly in section of another form of the invention.

Referring more particularly to the drawings, the numeral 10 designates generally a cleaning head which may be of any desired size and configuration. The cleaning head is hollow and is provided with a partition 11 dividing the same into a cup-

shaped receiving chamber 12 and an air inlet chamber 13. The chamber 12 is of a substantially cup shape formation, having an open bottom which latter is adapted to be placed against and moved over the surface to be renovated. The chamber 13 is provided with any desired number of outlet openings 15, extending through the bottom thereof preferably in close proximity to the bottom of the chamber 12, and form communication between the two chambers so that when the cleaning head is placed against and moved over the surface or article to be renovated and closed thereby, the openings 15 will also be moved over the surface.

The chamber 13 is provided with an inlet 16 and the chamber 12 is provided with an outlet 17. A fan 18 is suitably mounted and is operated by a suitable motor 19. The fan casing forms part of the cleaning head and has communication with the chamber 12, so that when the motor is operated, a blast of air currents will be created and will be discharged through the air inlet chamber 13 and out of the openings 15, against the surface to be renovated, and into the chamber 12, causing the surface against which the blast has been directed to become cleaned, as the foreign particles will be dislodged therefrom and discharged into the chamber 12 through the open bottom thereof. The air currents thus formed by the fan will cause a circulation through the fan chamber and will be discharged through the opening 17 into a passage 20, from where they will be driven through the passage 20 to be discharged into a separator 21.

The separator is preferably in the form of a tank which holds a quantity of liquid 22, such as water or the like for washing the air, and mounted within the separator tank 21 are a series of reticulated members 23 which revolve about a shaft 24. The members 23 are arranged within the path of the moving air currents, which are discharged into the separator 21 through the opening 24 to strike the members 23 and rotate them, causing them to be successively moved through the liquid 22. This operation not only filters or sifts the dust from the incoming air, but causes the foreign particles of dirt to be deposited in the receptacle, which latter is provided with a clean-out plug 25.

Leading from the separator through the outlet opening 26, is a pipe 27 which has communication with the inlet 16 of the chamber 13 of the nozzle 10, so that the air currents passing out of the separator 21 under pressure, will be forced through the pipe 27 into the chamber 13 of the nozzle and out of the outlet opening 15, as a blast, directed to the surface to be renovated. This blast dislodges the dirt and foreign particles from the surface and discharges or directs them into the chamber 12.

If desired one or more rollers 28 may be provided for supporting the weight of the machine and a handle 29 is also provided which is pivotally connected as at 30 with the machine, so that the machine can be readily manipulated and the openings 15 may be moved over the surface to be renovated.

In the form of the invention shown in Fig. 5, the cleaning head 32 is adapted to be placed in contact with the surface to be renovated and the fan 33 which is operated by the motor 34 operates in a chamber 35 which has communication with the head. Leading from the chamber 35 is a tube or passage 36 which has communication with the bag 37, of any desired size and configuration and constructed of any suitable material. This bag forms a receptacle for the dirt and foreign particles removed from the surface and is provided with an open end having a securing means 38 applied to such end to hold the same closed.

The bag is detachably connected with the tube or passage 36 so as to be readily removed therefrom and a flexible member 39 may be provided for supporting the other end of the receptacle as is usual in devices of this character, from the handle 40.

Arranged within the bag or receptacle 37 is a partition 40 which forms a filter or screen and is constructed of any suitable material which will permit the air currents to pass therethrough and remove the dirt and foreign particles from the dust laden air.

The partition divides the bag or receptacle into two compartments 42, 43, the former receiving the deposit of dirt and the latter forming an exit chamber for the clarified air. Removably connected with the bag or receptacle and having connection with the chamber 43 is another tube or pipe 44, which also has communication as at 45 with the nozzle 32.

The operation of this form of the invention is the same as that shown in Fig. 1, that is to say, an air blast is created by the fan 33 which discharges the air from the chamber 35 through the passage 36 into the receptacle 42. The air being filtered passes through the partition 41 into the chamber 43, from there through the pipe 44 back to the head 32 to be discharged against the

surface to be renovated and these air currents are picked up by the fan 33 and again forced through the air circulation passage so that the same air currents can be used over and over again.

With this improved construction it will be manifest that the blasts of air currents are directed back to the same portion of the surface to be renovated, thereby thoroughly removing all of the dirt and foreign particles from the surface. By forcing the air under the machine and causing it to enter the chamber 12, the weight of the machine will be lifted from the floor, and which weight is ordinarily caused in other machines by the vacuum or suction created in the cleaning head, which weight results in increasing the effort necessary to manipulate the machine. With the present construction and by relieving the weight by the air lift, the wear on the fabric over which the machine passes will be greatly reduced. It will also be manifest that the air which is directed through the openings 15 is clarified, and the same air current may be used over and over again, and the impure air will not be discharged into the room as is the case with other machines. Obviously the separator 21 may be provided with a removable closure 31 if desired.

The openings 15 are preferably in the form of independent openings arranged so as to extend transversely of the nozzle 10, and they may be arranged at any desired angle with respect to the surface to be renovated, to produce the best results.

While the preferred forms of the invention have been herein shown and described, it is to be understood, that many changes may be made in the details of construction and in the combination and arrangement of the several parts, without departing from the spirit of this invention, and therefore it is desired that the drawings herewith submitted are to be considered as being merely diagrammatic.

Obviously the apparatus may be of any desired size and configuration and constructed of any suitable material.

What is claimed as new is:

1. In a self-contained renovator, the combination of a cleaning head having an open bottom, a partition in said head dividing the head into a cup shaped chamber and an inlet chamber, said inlet chamber having communication with the said cup shaped chamber adjacent the bottom thereof, a fan chamber forming a part of and having open communication with the said cup shaped chamber, and a fan in the fan chamber, there being an air outlet passage leading from the said fan chamber and discharging into the said inlet chamber.

2. In a self-contained rénovator, the combination of a cleaning head having an open

bottom, a partition in said head dividing the head into a cup shaped chamber and an inlet chamber, said inlet chamber having communication with the said cup shaped chamber 5 adjacent the bottom thereof, a fan chamber forming a part of and having open communication with the said cup shaped chamber, and a fan in the fan chamber, there being an air outlet passage leading from the said 10 fan chamber and discharging into the said inlet chamber, said fan being disposed intermediate the said inlet chamber and the outlet of the said fan chamber.

3. In a self-contained renovator, the combination of a cleaning head having an open bottom, a partition in said head dividing the head into a cup shaped chamber and an inlet chamber, said inlet chamber having communication with the said cup shaped chamber 15 adjacent the bottom thereof, a fan chamber forming a part of and having open communication with the said cup shaped chamber, and a fan in the fan chamber, there being an air outlet passage leading from the said 20 fan chamber and discharging into the said inlet chamber, the outlets from the said fan chamber and the air inlet chamber being arranged in different horizontal planes.

4. In a self-contained renovator, the combination of a cleaning head having an open bottom, a partition in said head dividing the head into a cup shaped chamber and an inlet chamber, said inlet chamber having communication with the said cup shaped 25 chamber adjacent the bottom thereof, a fan chamber forming a part of and having open communication with the said cup shaped chamber, a fan in the fan chamber, there being an air outlet passage leading from the 30 said fan chamber and discharging into the said inlet chamber, and a separator connected with the said air passage to receive the dust laden air therefrom.

5. In a self-contained renovator, the combination of a cleaning head having an open bottom, a partition in said head dividing the head into a cup shaped chamber and an inlet chamber, said inlet chamber having communication with the said cup shaped 35 chamber adjacent the bottom thereof, a fan chamber forming a part of and having open communication with the said cup shaped chamber, and a fan in the fan chamber, there being an air outlet passage leading from the 40 said fan chamber and discharging into the said inlet chamber, the communicating passage between the air inlet chamber and the said cup shaped chamber being disposed in close proximity to the surface to

be renovated and arranged in an inclined 60 plane with respect to said surface.

6. In a self-contained renovator, the combination of a cleaning head, having an open bottom, a partition dividing the head into a cup shaped receiving chamber and an air 65 inlet chamber, said chambers having communication adjacent the bottoms thereof, a fan chamber surmounting and forming a portion of the said cup shaped chamber, a fan in the chamber, a conduit leading from 70 the fan chamber and discharging into the said air inlet chamber, an operating handle connected with the head, and a separator having communication with said conduit.

7. In a self-contained renovator, the combination of a cleaning head, having an open bottom, a partition dividing the head into a cup shaped receiving chamber and an air 75 inlet chamber, said chambers having communication adjacent the bottoms thereof, a fan chamber surmounting and forming a portion of the said cup shaped chamber, a fan in the chamber, a conduit leading from 80 the fan chamber and discharging into the said air inlet chamber, an operating handle connected with the head, and a separator having communication with said conduit, the communicating passage between the chambers discharging directly against the 85 surface to be renovated and in such a manner that the blast of air will relieve the weight of the renovator upon said surface.

8. In a self-contained renovator, the combination of a cleaning head, having an open bottom, a partition dividing the head into a cup shaped receiving chamber and an air 90 inlet chamber, said chambers having communication adjacent the bottoms thereof, a fan chamber surmounting and forming a portion of said cup shaped chamber, a fan in the chamber, a conduit leading from 95 the fan chamber and discharging into the said air inlet chamber, an operating handle connected with the head, a separator having communication with said conduit, and a 100 roller connected with the head and coöperating with the forward edge thereof, but spaced from said edge for supporting and guiding the head.

In testimony whereof I have signed my 110 name to this specification, in the presence of two subscribing witnesses, on this 20th day of January, A. D. 1917.
